Des. 196,322
Patented Sept. 17, 1963

196,322

BRACKET HOOK

Harold O. Pawsey, 1200 Lucretia Ave., San Jose, Calif.

Filed Dec. 31, 1962, Ser. No. 73,006

Term of patent 14 years

(Cl. D54—1)

FIG. 1 is a perspective view of a bracket hook embodying my new design therefor.

FIG. 2 is a side view of FIG. 1.

FIG. 3 is a top plan view of FIG. 2.

I claim:

The ornamental design for a bracket hook, as shown.
